SMOKING STAND

Elon G. Pratt, New York, N. Y., assignor to Smokador Manufacturing Co., Inc., Bloomfield,
N. J., a corporation of Delaware

Application June 13, 1950, Serial No. 10,478

Term of patent 14 years

(Cl. D85—2)

To all whom it may concern:

Be it known that I, Elon G. Pratt, a citizen of the United States, residing at New York, in the county of New York and State of New York, have invented a new, original, and ornamental Design for a Smoking Stand, of which the following is a specification, reference being had to the accompanying drawing, forming part thereof.

Fig. 1 is a perspective view of a smoking stand, showing my new design;

Fig. 2 is an enlarged view in side elevation of the smoking stand shown in Fig. 1;

Fig. 3 is a top plan view of the stand shown in Fig. 2; and

Fig. 4 is a cross-sectional view taken substantially in the plane of the line 4—4 of Fig. 2.

I claim:

The ornamental design for a smoking stand, substantially as shown.

ELON G. PRATT.
